UNITED STATES PATENT OFFICE.

FRANK T. PIERSON AND WALTER S. McNALLY, OF CHICAGO, ILLINOIS.

FOLDING TABLE.

1,260,941.

Specification of Letters Patent. Patented Mar. 26, 1918.

Application filed February 15, 1917. Serial No. 148,736.

To all whom it may concern:

Be it known that we, FRANK T. PIERSON and WALTER S. McNALLY, both citizens of the United States, and residents of Chicago, 5 in the county of Cook and State of Illinois, have invented certain new and useful Improvements in Folding Tables, of which the following is a specification.

Our invention relates to folding tables, 10 particularly to that class in which side sections are to be raised into the plane of the top section or to be dropped to hang down from the edges of the top section.

The object of the invention is to produce 15 improved means for readily permitting opposite leg structures to be drawn apart to support the raised side sections of the table top and to be brought together to permit such side sections to be dropped. Furthermore, 20 the object is to produce improved extensible interconnecting mechanism between the leg structures for rigidly holding the leg structures in parallelism with each other particularly when the structures are drawn 25 apart, such rigid interconnection keeping the top side sections horizontal and preventing sagging thereof when the table is unfolded. Generally speaking, the invention comprises I-beams secured to the under side 30 of the central section of the table top, and channel beams secured to the opposite leg structures for telescopically coöperating with the I-beams to readily permit the leg structures to be separated or brought together. 35 Rollers are preferably provided at the ends of the I-beams and channel beams to reduce friction.

On the accompanying drawings the various features of our invention are shown embodied in a table structure. In these drawings

Figure 1 is a transverse cross-sectional view of the unfolded table on a vertical plane just outside the extensible interconnecting mechanism,

Fig. 2 is a sectional view on plane 2—2, Fig. 1,

Fig. 3 is a view similar to Fig. 1, showing the table folded, and

Fig. 4 is a plan view partly in section on plane 4—4, Fig. 1.

The table top comprises the central longitudinal section 10 and the two side sections or leaves 11 and 12 hinged to the central section by suitable hinges 13 and 14. Extending transversely of the top section 10

near its ends and secured to the under side thereof are the I-beams 15 and 16, screws 17 being shown passing through the beam flanges for securing them in place. The 60 opposite leg structures *a* and *b* comprise respectively the top beams 18 and 18' at whose ends the legs 19, 20 and 19', 20' are secured. Associated with the I-beam 15 are two channel bars 21 and 21' which are secured at their 65 outer ends to the tops of the leg structure beams 18 and 18' as by means of angle plates 22 and 22'. These channel bars project into the opposite compartments of the I-beam with their flanges extending toward 70 the I-beam web between the upper and lower flanges thereof. At the opposite ends of the I-beam 15 and extending into the opposite compartments, the pins 23 and 24 are secured to the I-beam web and these pins journal rollers 25 and 26 which extend between the upper and lower flanges of the channel bars 21 and 21' respectively. At the inner ends of these channel bars pins 27 and 27' are secured to the webs and journal rollers 75 80 28 and 28' which extend between the upper and lower flanges of the I-beam, the ends of the side flanges of the channel bars being cut away as indicated at 29 to make clearance for these rollers. At the opposite ends 85 of the leg structures a similar arrangement is provided comprising channel bars 21 and 21' secured to the beams 18 and 18' to co-operate with the I-beam 16 and having the roller 28 and 28' at their ends to engage between the I-beam flanges, and the I-beam having the rollers 25 and 26 at its ends for engaging between the upper and lower flanges of the channel bars. Although only 90 two interconnections are shown, each comprising an I-beam and coöperating channel bars, it is evident that any number of such interconnections may be provided depending upon the size of the table.

With the arrangement described, the opposite leg structures *a* and *b* can be readily brought together as shown in Fig. 3, or separated as shown in Figs. 1 and 4. The separating movement is limited by the engagement of the rollers 28 and 28' with the rollers 25 and 26. The various rollers are of diameters to fit snugly between the respective upper and lower flanges of the I-beams or channel bars, there being just sufficient clearance to permit the rollers to rotate 110 when the leg structures are shifted. With this arrangement the channel bars will be

kept parallel with the I-beams and the table legs will at all times be vertical. The rollers could, of course, be omitted and the channel bars fitted snugly between the flanges of the 5 I-beams, but this would cause considerable friction. By providing the rollers, friction is eliminated and the leg structures on very heavy tables can be readily shifted with little effort.

10 When the leg structures are brought together to be within the side edges of the top section 10, the leaves 11 and 12 are free to drop and to hang in vertical position. When the leg structures are separated the 15 leaves will rest thereon and be held in horizontal position. We have shown spacer boards or plates 30 and 31 secured to the under sides of the leaves, which boards are engaged by the tops of the channel bars 20 when the leg structures are separated. These spacer boards also strengthen the leaves and prevent warping thereof. In order to give a more finished appearance to the table the tops of the leg structures have 25 side walls or rails 32 and 32' and the end walls or rails 33 and 33', these walls inclosing the outer ends of the channel bars. When the table is to be unfolded the leaves need not necessarily be raised to horizontal 30 tal, but they can be automatically lifted by the leg structures when they are separated. Referring to Fig. 3, when the leg structures are separated the side walls 32 and 32' will engage with and raise the leaves, and the 35 inner edges *c* and *d* of the plates 30 and 31 are preferably beveled to be engaged by the upper edges of the walls 32 and 32' during final outward shifting of the leg structures, such shifting causing the leaves to be lifted 40 to horizontal position, as clearly shown in Fig. 1.

We thus produce a table of durable construction and neat appearance whose opposed leg structures can be brought closely 45 together to permit the dropping of the side leaves, or which can be readily separated to support the leaves in horizontal position, the extensible interconnecting mechanisms operating freely but keeping the leg structures at all times rigid so that the legs are 50 at all times perpendicular. It is not necessary to use the I-beams shown as any supporting frames can be employed which provide upper and lower flanges or tracks for 55 the rollers on the channel bars.

We do not, therefore, desire to be limited to the exact construction and arrangement

shown and we desire to secure the following claims by Letters Patent:

1. In a folding table, the combination of 60 a top, leaves hinged at the longitudinal sides of said top to swing downwardly or into horizontal position, frames secured to the under side of said top providing upper and lower rails, opposed leg structures, sets 65 of channel bars secured to and extending inwardly from the opposed leg structures and into the opposite sides of the respective frames between the flanges thereof, a roller pivoted at the inner end of each channel bar to engage between the rails of the respective frames, and a roller pivoted at each end of each frame for engaging between the flanges of the respective channel bars, whereby said leg structures may be 70 brought closely together under the table top to permit dropping of the leaves or to be spread apart into position underneath the leaves to support them in horizontal position, the engagement of said rollers 75 with the flanges of the frames and bars keeping the frames and bars at all times parallel and the legs of the leg structures vertical.

2. In a folding table, the combination of 80 a top, leaves hinged to the top sides to hang downwardly or to be swung upwardly into horizontal position, I-beams secured to the under side of said top each affording upper and lower rail flanges at its opposite sides, 85 opposed parallel leg structures each having legs, pairs of channel bars, the bars of each pair being secured to the opposed leg structures and engaging at the sides of the respective I-beam between its flanges, rollers 90 pivoted at the opposite ends and sides of each I-beam for engaging between the upper and lower flanges of the respective channel bars, and a roller at the end of each channel bar for engaging between the respective flanges of the I-beam, whereby said 95 leg structures may be shifted toward and away from each other to permit downward swing of the leaves or to support the leaves in horizontal position, the coöperation of 100 said rollers with the respective flanges serving to keep the channel bars parallel with the I-beams to hold the legs vertical at all 105 times.

In witness whereof we hereunto subscribe 110 our names this 8th day of February, A. D. 1917.

FRANK T. PIERSON.
WALTER S. McNALLY.
